UNITED STATES PATENT OFFICE

CHARLES CLINTON ALVORD, OF WORCESTER, MASSACHUSETTS, ASSIGNEE TO
WORCESTER LOOM WORKS, OF WORCESTER COUNTY, MASSACHUSETTS

TRANSFER COMB

Application filed April 26, 1930. Serial No. 447,585.

My invention relates to the transfer comb commonly used to secure in properly spaced relation the free ends of the tuft yarns on Axminster tube frame spools. These combs are applied to the yarn strands at the setting frame and remain with the spools while they are in storage. They keep the yarns in proper order preparatory to being threaded through the tubes of tuft yarn frames. This operation which involves the use of the transfer comb is well described in the threading machine patent to Hathaway and Lea #1,153,864 of Sept. 14, 1915.

The type of transfer comb now in use is clearly shown in Fig. 11 of that patent. It will be noted that Hathaway and Lea employ a cap piece 18 to retain the yarns. It is the main object of my invention to produce a transfer comb which will retain the yarns without the use of such a cap piece. Another object contemplates the use of suitable mechanism to engage the comb with the yarn strands and other objects will be described and pointed out in the appended claims.

My invention will be best understood by reference to the following description when taken in connection with the accompanying illustration of one specific embodiment thereof, while its scope will be more particularly pointed out in the appended claims.

In the drawings, Fig. 1 is a side elevation of one preferred mechanism for engaging the transfer comb with the yarn strands. Fig. 2 is a plan of Fig. 1; Fig. 3 is a fragmentary enlarged perspective view of one of the transfer comb squeezers. Fig. 4 shows my new transfer comb enlarged and in perspective, part of the teeth being shown as normally closed, while others are shown flexed, and ready to receive the yarn strands. Fig. 5 is an enlarged fragmentary front view of my transfer comb operatively positioned with respect to the rear squeezer; and Fig. 6 is a view similar to Fig. 1 showing the mechanism swung down to its low position.

As will be seen by Fig. 4 my new transfer comb is formed of a piece of sheet metal 1, provided with a series of teeth 2, the base of each tooth being substantially half as wide as the pitch or center to center distance

between adjacent teeth, thus forming yarn receiving slots 3 for the spaced retention of pile yarn strands, one of which is shown as 4. The apices of the teeth are substantially in contact at 5 so as normally to close the 55 yarn receiving slots 3. Transfer combs are often 54" long and since the comb body 1 is of relatively light, springy material I prefer to employ two stiffeners 6 and 7 riveted or otherwise secured to the body to provide 60 the necessary rigidity. To permit the broadside entrance of the pile yarn strands I provide means to flex the teeth alternately sideways by a mechanism such as that shown in Figs. 1 and 2. The effect of this flexing on 65 the comb is shown in Fig. 4 at the left hand end of the view where it will be seen that sufficient opening is provided to permit the broadside entrance of yarn strands. When the flexing force is removed the teeth will 70 spring back into line thus closing the yarn entrances. Stiffeners 6 and 7 also serve as lateral guards for the teeth so that no tooth can be bent sideways beyond its elastic limit.

In order to show the relative position of 75 my device on the well known Collins setting frame described in Patent 1,185,633, I have indicated tension rollers 8 and yarn spool 9 corresponding respectively to Collins rollers B and yarn spool E. Reed comb 10 is also 80 the same as his comb D.

To the setting frame sides 11 I bolt brackets 12 which provide bearings for cam shaft 13. Fixed girt 14 extending between brackets 12 serves as a fulcrum for swing stand 15 85 to which is screwed toothed member 16. The teeth on this member are clearly shown in Fig. 3 and are of the same spacing as the teeth on the transfer comb. Resting upon the planed feet of member 16 is another 90 member 17 similarly equipped with teeth. Member 17 is registered longitudinally with respect to member 16 by being slidably mounted on dowel pins 18 to assure that the 95 teeth on the two members are in alignment. It will be noted that every other tooth is provided with a projection 19, such projections occurring on the odd numbered teeth on one member and the even numbered teeth on the other member. When the comb clamp is 100

dropped between these two squeezer members 16 and 17 and allowed to rest upon dowel pins 18 as shown in Figs. 1 and 5 it will be seen that the projections are opposite the apices of the teeth. Now if pressure is applied to member 17 tending to urge it against the transfer comb, the projections on the two squeezer members will, in cooperation with each other, flex alternately sideways the transfer comb teeth to permit the broadside entrance of the pile yarn strands. The maximum offset possible is definitely fixed by the height of the projections as it cannot exceed an amount = $\frac{H}{2}$ in which H = the height of

the projection. Under maximum flexure there is a certain calculable stress in the comb teeth. I so proportion the height of the projections and the dimensions of the comb teeth that the maximum stress cannot exceed the elastic limit of the material from which the transfer comb body 1 is formed. Thus when the squeezing pressure is removed the transfer comb teeth will resume their normal positions in the same plane. By this unique construction I eliminate all possibility of the stress in the comb teeth exceeding the elastic limit of the metal as a permanent set or bend in the teeth would thereby be produced. To position the transfer comb in proper alignment with respect to the squeezer teeth I provide two registering pins 20 located immediately adjacent the ends of the comb to prevent longitudinal movement.

When the operative inserts the transfer comb between the squeezer members the mechanism is in the lower position as shown in Fig. 6. There are two similar cams 21 keyed to cam shaft 13. Rollers 22 journaled upon studs fast in swing stand 15 bear on these cams. The cam lobes upon movement of the cam shaft by handle 13' rotate the swing stand to its upper position as in Fig. 1. As the squeezer members rise the pile yarn strands start to enter their proper slots in the squeezer members but they cannot enter the transfer comb yet as the squeezers have not been forced together. They are thus lifted slightly above their normal position and placed under added tension preparatory to snapping into the transfer comb after the teeth have been flexed.

Referring to Fig. 5 it will be seen that the pointed apices of the squeezer comb teeth extend somewhat above the substantially arcuate apices of the transfer comb teeth.

The squeezer comb being milled from the solid naturally is of a higher degree of accuracy than the punched transfer comb and it is for that reason that I prefer to extend the apices of the squeezer above the transfer comb in order that the ribbon of yarns may be initially contacted and separated by the more accurate of the two combs. Once the yarn strands have entered between the teeth

of the squeezer comb they will be guided by them into their respective slots in the transfer comb. I prefer to use the rounded form of apex shown on the transfer comb as there is much less chance of this shape catching on the yarns on adjacent spools when in storage or at other times.

I will now describe one good form of mechanism which may be employed to flex the comb teeth. There is a fixed girt 23 extending between two depending lugs on swing stand 15. Two cam levers 24 fulcrumed upon this girt are provided with rollers 25 bearing upon similar cams 26 keyed to cam shaft 13. The upper ends of cam levers 24 terminate in lugs 27 tapped to receive adjusting screws 28 so situated that the heads bear against the front squeezer member 17. Continued rotation of cam shaft 13 forces the front squeezer member rearwardly to flex the comb teeth as previously described. I provide screws 29 tapped into lugs integral with the setting frame sides 11 to bear against the hubs on cam levers 24. The purpose of these screws is to prevent any further lift of swing stand 15 under the squeezing pressure exerted by cam lever 24. As soon as the comb teeth are fully flexed the pile yarn strands snap down therein and squeezer cam 26 immediately relieves the pressure allowing the comb teeth to spring back into line with each other. The front squeezer member retracts sufficiently under the action of spring 30 to provide sufficient clearance for the squeezers, upon continued rotation of cam shaft 13, to swing down back to the position in Fig. 6 leaving the transfer comb hanging on the ribbon of pile yarn strands and in easy grasping position for the setting frame operative.

Summarized briefly, one revolution of cam shaft 13 swings the transfer comb up against the pile yarn strands, flexes the teeth to permit broadside entrance of the yarns, closes the teeth, opens the squeezers and then drops them allowing the transfer comb to remain hanging on the yarn strands. This entire cycle may be performed with great rapidity, much quicker in fact than the older method of picking up a cover piece and securing it to the transfer comb. Moreover there is no possibility of the yarns coming out of my transfer comb during the many handlings it receives during storage and threading.

While I have shown but one good embodiment of my invention I wish it understood that various modifications may be made without departing from the spirit of my invention.

I claim:

1. As a new article of manufacture, a transfer comb for tuft yarns in which the teeth are relatively flexible, the apices of said teeth normally being substantially in contact so as positively to prevent broadside egress of the yarns.

2. A transfer comb for tuft yarns provided with a series of relatively flexible teeth, the base of each tooth being less than the pitch of the teeth so as to form yarn receiving slots between adjacent teeth, the apices of adjacent teeth normally being substantially in contact with each other so as practically to close the yarn receiving slots, whereby yarns positioned in said slots are retained positively against broadside escape.

3. In combination a transfer comb for tuft yarns comprising a piece of sheet metal provided with a series of teeth, the base of each tooth being substantially half as wide as the center to center distance of the teeth so as to form yarn receiving slots between adjacent teeth, the apices of adjacent teeth normally being substantially in contact with each other so as practically to close the yarn receiving slots, with means adapted to flex the teeth sufficiently to provide broadside entrances for yarn strands into said slots.

4. In combination, a transfer comb for tuft yarns provided with teeth adapted to be flexed sideways to permit the broadside entrance of tuft yarns therebetween with means for flexing alternate teeth of said comb, said means being shaped and arranged so that the tensile stress in the teeth when fully flexed is below the elastic limit of the transfer comb material whereby the teeth will return to their normal position when the flexing means is retracted.

5. In a device for flexing the teeth of a transfer comb, two opposing members each provided with a series of aligned teeth, the even numbered teeth on one member and the odd numbered teeth on the other member being equipped with projections formed to flex sideways alternately the teeth of a transfer comb interposed therebetween when said members are forced toward each other, the height of the projections on said members being such that the device is rendered incapable of flexing the teeth beyond a predetermined amount.

6. As a new article of manufacture, a transfer comb for tuft yarns in which the teeth of said member must be under stress to permit broadside entrance of the tuft yarns therebetween,

7. The combination with a flexible tooth transfer comb for tuft yarns of a member secured thereto serving as a stiffener member and also as a lateral guard for the teeth whereby excessive sidewise flexing is prevented.

8. A transfer comb for tuft yarns in which the apices of the comb teeth normally are substantially in contact so as positively to prevent broadside escape of yarns positioned between said teeth.

9. Mechanism for engaging a flexible tooth transfer comb with a ribbon of yarns comprising a squeezer adapted to receive said

comb and means, first to actuate said squeezer to flex the teeth of said comb and then to move said comb into operative engagement with said yarns, whereby said yarns are threaded broadside.

10. A transfer comb for spacing and retaining pile yarn ends comprising a series of alternating tooth and slot formations, said teeth being provided with integrally-formed yarn retainers positively to prevent broadside escape of yarns positioned in said slot formations.

11. That method of engaging a flexible tooth transfer comb with a ribbon of yarns which comprises placing the comb within a squeezer, actuating the squeezer so as to flex the comb teeth to permit broadside entrance of the yarns, raising the ensemble to permit the yarns to enter between the teeth of the comb, releasing the squeezer to permit the broadside threading entrances on the comb to close and then lowering the squeezer leaving the transfer comb suspended on the yarns.

12. The method of engaging a transfer comb having tooth apices of substantially blunt formation with a ribbon of yarn strands which consists in temporarily positioning said transfer comb adjacent an auxiliary comb having tooth apices of substantially pointed formation, the apices of the transfer comb being located slightly below the apices of the auxiliary comb, and moving the ensemble toward the ribbon of yarns to permit the pointed apices to initially contact and separate the ribbon of yarn strands to guide them accurately into place between the transfer comb teeth.

13. A transfer comb for tuft yarns provided with yarn spacing teeth which are shaped to prevent broadside passage of the yarns therebetween, said teeth being adapted to be moved apart from each other in a direction substantially parallel to the yarn strands so as to provide free broadside passage therefor.

In testimony whereof I have hereunto affixed my signature.

CHARLES C. ALVORD.
